CLAIM

The ornamental design for a security clip for preventing theft and accidental wallet loss, as shown and described.

DESCRIPTION

FIG. 1 is a perspective view of a theft and accidental loss protector showing my new design;

FIG. 2 is a rear perspective view thereof;

FIG. 3 is a fragmentary element of a modified embodiment of the catching element illustrated in FIG. 1;

FIG. 4 is a front elevation view of the theft and accidental loss protector; and

FIG. 5 is still a further modified embodiment of the security clip illustrated in FIG. 1.

FIG. 1

FIG. 2

FIG. 3

FIG. 4

FIG. 5
